Res. 2374

David Shinnell of Buffalo, N.Y.
Letters Patent No. 2374, Date July 24, 1866.
Design for Trade Marks

The Schedule referred to in this Letters Patent, and making part of the same.

To all whom it may concern:

Be it known that I, David Shinnell of Buffalo in the County of Erie and State of New York, have originated or designed a new Design for a Trade Mark, of which the following is a full, clear, and exact description, reference being had to the annexed drawings, making part of this Specification.

The Design as engraved on a suitable block contains all the matter shown in the drawings except the Directions, which being printed by movable type are not the subject matter of a patent.

The body of the Design is printed in any color at the head of the block in uncolored letters or letters having the color of the paper, on which the Design is printed, another following words printed in reverse, "Principal Dep't 172 Niagara Street Buffalo N.Y." below these are the words following, viz: "Shinnell's Bullion & Waching Crystal, Shinnell Fisher & Co, proprietors

That I claim as my invention and desire to secure by Letters Patent is,

The Design for a Trade Mark as shown and described, in testimony whereof I have signed my name to this Specification in the presence of two subscribing witnesses.
